ALPHONSE LAFON, OF DETROIT, MICHIGAN, ASSIGNEE OF ONE-HALF TO ALBERT B. BOYNTON, OF SEWAREN, NEW JERSEY.

VALVE FOR INTERNAL-COMBUSTION ENGINES.

1,160,292.

Specification of Letters Patent. Patented Nov. 16, 1915.

Application filed May 14, 1912. Serial No. 697,173.

To all whom it may concern:

Be it known that I, ALPHONSE LAFON, a citizen of the United States, and a resident of Detroit, in the county of Wayne and State of Michigan, have invented a new and Improved Valve for Internal-Combustion Engines, of which the following is a full, clear, and exact description.

My invention relates to an improvement 10 in valves for internal combustion engines, and the object thereof is to produce an improvement of this nature which will be simple and easy to make and advantageous in operation, providing for efficient scaveng- 15 ing of the power cylinder without the use of auxiliary pumping devices, and likewise allowing of the efficient oiling of the parts.

I attain the above-mentioned objects and advantages by means of a valve that consists 20 of a hollow body having passages and ports formed therein, the whole being made in one piece and being driven by any appropriate connection from the engine crank shaft.

Reference is to be had to the accompanying 25 drawings forming a part of this specification, in which the same characters of reference indicate the same parts in all the views.

Figure 1 represents a sectional view 30 taken through the power cylinder in which the valve is mounted, the plane of section being at right-angles to the axis of rotation of the valve, and the valve itself being shown in end elevation, the point of view 35 being from the side on which the flywheel is located; Fig. 2 represents a view similar to Fig. 1, but showing the valve viewed from the opposite side; Fig. 3 is a sectional view on the line 3—3 of Fig. 1, looking in 40 the direction of the arrow; Fig. 4 is a transverse sectional view of the valve looking into the same from the side which is located adjacent the flywheel; and Fig. 5 is a similar 45 sectional view looking into the valve toward the side adjacent the flywheel.

On the drawings, the numeral 1 represents a power cylinder in which moves a piston 2. This power cylinder is provided 50 with the usual water jacket inclosing spaces 3 for the passage of cooling liquid, and is provided with a head 4, through which extends an exhaust passage 5 and an inlet passage 6. The exhaust passage 5 is bifurcated at its inner end to provide a pair 55

of branches 7; and the inlet passage 6 communicates at its inner end with a pair of similar branches 8, these branches terminating in ports with which register ports formed in the body of the valve itself on 60 different sides of the central transverse plane of the said valve.

The valve itself is spherical in form, and it is received in a spherical pocket or recess 9 formed in the head and top of the cylinder 1. The valve itself is shown at 10, and it is cut away over nearly half a circumference, as shown at 11, to establish communication between the hollow interior thereof and the working chamber of the cylinder 1. 70 This valve is mounted on a spindle 12 which extends therefrom at one end, and this spindle 12 is provided with a duct 13 which registers with a similar duct in the body of the valve, this duct opening 75 through the outside surface of the valve 10, the spindle 12 of course being made rigid with the valve body to rotate the same. The duct 13 terminates in a passage 14 which opens through the side of the spindle 80 in position to register with an oil passage 15, to which leads an oil pipe 16. The relative location of the passages 14 and 15 is such that these two spaces will communicate on the intake stroke of the piston 2 to fill 85

the duct 13 with oil, and the oil in this duct will be caused to flow out through the end thereof by the centrifugal force of the rotating valve 10.

The valve is provided at a point opposite 90 the spindle 12 with a journal 17 rigid with the valve and in axial alinement with the spindle 12, as will be readily understood. This journal is received in a bearing formed in the top of the cylinder 1, and the 95 lower face of the head 4; and the valve rotates on the spindle 12 and journal 17 when in operation.

19 is a port which passes through the shell of the valve on the same side as the 100 spindle 12, and adjacent this port 19 is a similar port 20. 21 is a third port of greater angular extent than either of the ports 19 or 20, located on the same side of the valve 10 as the two ports above mentioned; and 22 is a tube or conduit cast inside the valve body 10 and terminating in a lip 23, which is located adjacent the port 20. Another port is shown at 18, and this port is located at the opposite end of the 110

valve and in alinement with the port 19. As shown in Fig. 1, the cut-away portion 11 of the valve extends between the port 18 and the ports 19 and 20, and this cut-away portion establishes communication with the interior of the valve and the power chamber and cylinder 1, as above stated.

24 is the usual igniter, this igniter passing inward from the side of the cylinder through the journal 17, which is made hollow for this purpose, and terminating in spark points inside of the valve body 10.

The spindle 12 projects outward through the cylinder wall and carries on its outer end a gear or sprocket wheel shown diagrammatically in broken lines in Fig. 3, and this wheel is to be connected by means of a chain or by intermediate gears to the crank shaft, so that the valve 10 can be operated in step and in proper speed relation with the engine.

The branch passages 7 terminate in ports which are of substantially the same area at opposite ends of the valve 10, but the branches 8 terminate in ports of unequal area, the larger at the same end of the valve as the port 18, this port of larger area being shown in Figs. 1 and 4. The opposite edges of the ports 7 and 8 are the same distance apart at both ends of the valve, but the adjacent edges of the port 7 and the port of larger area 8 at the same end of the valve as the port 18, are of course closer together than the adjacent edges of the ports 7 and 8 at the opposite end of the valve. As a result, the port 18 will come into registry with the port 8 of larger area before the port 19 will come into registry with the port 8 of smaller area at the other end of the valve.

40 The valve is rotated around the spindle 12 and journal 17 as an axis. All the ports are closed at the beginning of the power stroke, the position of the parts at this step in the cycle of the operation of the engine 45 being shown in Fig. 1, the valve communicating with the power chamber in the cylinder 1 through the opening 11. The rotation is clockwise referring to Fig. 1. At the end of the power stroke the port 19 comes into 50 registry with the port at the end of the passage 7 at the same end of the valve, and the port 18 comes into registry with the port 7 at the opposite end, and on the return of the piston the gases are forced out through 55 these ports and passages 7 and exhaust conduit 5. After the ports 18 and 19 are past registering position with the ports at the ends of the passages 7, the port 20 comes into registry with the port 7 on the flywheel 60 side of the valve, and just before this registering takes place between the port 20 and adjacent port 7, the opening 11 through the valve moves out of registry with the adjacent end of the power chamber of the cylinder 1, so that the shell of the valve cuts off

communication between the power chamber or cylinder and the interior of the valve. At this instant, however, the port 21 moves into uncovered position adjacent the end of the cylinder, and the remaining gases of 70 combustion are forced therethrough and through the tube 22 and out through the port 20 and port at the end of the adjacent passage 7. The ejector action of the stream of gases passing through the conduit 22 75 clears the interior of the valve 10 of the burnt gases it contains, so that as little of the burnt gases as possible remain inside of the valve to dilute the fresh mixture which is drawn in to form the next fuel 80 charge.

To relieve the partial vacuum that would be formed by the burnt gases being ejected from the interior of the valve 10, the port 18 comes into registry with the enlarged port 8 85 before the port 20 and the port at the end of the adjacent passage 7 move out of communication with each other. Fresh mixture then starts to flow in, but little or none of this fresh mixture is lost by passing out through 90 the port 20 and the exhaust conduit 5. The valve is so timed that the mixture starts to flow into the valve 10 to relieve the partial vacuum formed therein before any of the 95 exhaust gases can flow backward into the valve; and before any of the mixture can flow outward after the exhaust gases, the movement of the valve 10 will destroy communication with the exhaust conduit, and the mixture in the interior of the valve 10 100 will then pass through the conduit 22 and port 21 to the cylinder of the engine. The further movement of the valve closes the intake and outlet ports and compression and ignition then result in proper order. 105

As stated above, Fig. 1 shows the parts in the position they occupy about the beginning of the firing stroke; and Fig. 2 represents the position which the valve and its 110 ports occupy about at the beginning of the suction stroke. The port 18 will register with the enlarged port at the end of the adjacent passage 8 before the port 20 moves entirely out of registry with the port at the 115 end of the adjacent exhaust passage 7, as above stated. Later on the port 19 will move into registry with the smaller intake port, and the two ports 18 and 19 will move out of registry with the ports at the end of the passages 8 about at the same instant. The operation of charging is finished after the port 20 has moved out of registry with the port at the end of the adjacent intake passage 8, as will be readily understood. 120

Figs. 4 and 5 show the valve and its ports in the positions they occupy about at the beginning of the exhaust stroke, and it will be understood that during compression the ports leading to the intake and exhaust conduits will be completely closed. The inte- 125 130

rior of the valve, however, will not be closed off from the interior of the cylinder during the compression stroke, for the reason that the port 21 will remain uncovered until the 5 nearest end of the cut-away portion 11 is uncovered, so that, during the compression stroke, communication will be established at all times with the interior of the cylinder 1 and the interior of the valve, either through 10 the conduit 22 or the opening 11. There are no projections on the inside or outside of my valve to serve as places on which carbon can be deposited, the end of the conduit 22 being rounded off at 23 opposite the port 20 to avoid this result. The ducts 15 and 15 will efficiently lubricate the valve, the oil flowing out through the inner end of the duct 13 by centrifugal force, and distributing itself evenly over the entire outer 15 surface of the valve 10. The cooling spaces 3 extend into the head 4, and the valve is at all times protected and cooled by the body thereof being in contact all the way around with the water jacket of the engine. The 20 pressure of the gases in the cylinder only serves to force the valve tighter against the head 4 of the cylinder. With a puppet valve located in the head this pressure will force oil out, making elaborate oiling devices necessary, but in my device the oil is forced to flow where it is most needed. It will be noted that on account of the fact that the cut-away portion 11 is establishing communication between the interior of the cylinder 30 1 and the interior of the valve at the time when ignition takes place, the rising pressure of the gases tends to expand the valve, and the stress of this expanding force naturally produces the greatest effect on the side 35 in which the cut-away opening 11 is formed. This causes the half of the valve in which the opening 11 is formed to be crowded more tightly against its seat, and any oil ever the outer portion of the surface of this part of 40 the valve is forced over on the other half of the valve, which is the upper half in the position of the parts shown in Fig. 1. Hence, the oil cannot escape, but is at all times retained between the valve and its 45 seat. When the pressure diminishes, owing to the out stroke of the piston and the consequent expansion of the gases, the valve is relieved of the stress put upon it, and once more runs free. The gases passing into the 50 chamber inside of the valve, and passing through the tube or conduit 22, cool the valve, and in so doing are heated, thus saving waste heat and facilitating the combustion. The ignition, when the same takes 55 place, causes the gas to burn in a spherical combustion chamber formed on the inside of the valve, and to expand through the opening 11 against the head of the piston 2. The valve rotates half as fast as the crank shaft, 60 thus reducing friction and wear and enabling the use of comparatively small ports. The so-called wire drawing of the gases is obviated by the fact that, while one port, namely, the port 19, is moving out of registering position, the other port 20 is opening, 70 and when the latter port is closed, the operation either of the exhausting or suction is nearly equal. Thus I avoid the jerky opening and shutting which are met with in valves of other types, and which are so destructive to the mechanism. The valve can be exactly timed, and the valve openings can be made of any desired size, as will be readily understood. Leakage is avoided by using a copper gasket between the cylinder 80 head and the top of the cylinder; and by discharging the hot gases from more than one point the heating effect is equalized and the warping of the parts prevented. Furthermore, the cold incoming gases are drawn 85 through several openings and partly through the same ports in the valve through which the exhaust gases are forced out, thus tending to keep all the parts at the same temperature. Furthermore, the fact that the 90 mixture is drawn in through several openings makes the mixing perfect and gives a very efficient combustion.

Having thus described my invention, I claim as new and desire to secure by Letters Patent:

1. In an internal combustion engine, a hollow valve body constituting a portion of the combustion chamber, and means for exhausting the products of combustion therefrom including a conduit in the valve body arranged to communicate at one end with the cylinder of the engine during the exhaust period, and opening at its other end within the valve and in close proximity to 100 the port through which the exhaust gases pass therefrom.
2. In a valve construction for internal combustion engines, the combination of a cylinder having an exhaust conduit and an intake conduit, branch passages leading from the inner ends of said conduits to the firing chamber of the engine, a hollow valve having ports in its end, said ports being in alignment with each other to control communication between said passages and said firing chamber, said ports and said passages being so located that the valve ports establish communication simultaneously with the exhaust passage while one of the ports opens communication with one of the intake passages in advance of the other port.
3. In a valve construction for internal combustion engines, the combination of a cylinder having an exhaust conduit and an intake conduit, each of said conduits terminating in branch passages at its inner end leading to the firing chamber of the engine, a hollow rotating valve to control commu- 120

nication between said passages and said chamber, said valve having a pair of ports in its opposite ends in alinement and a second port adjacent one of the said ports and following the same, and a conduit formed inside of said valve, said conduit opening through the valve at one end and having its other end located adjacent the second-named port, said second-named port and 10 said conduit serving to complete the exhaust from said firing chamber.

4. In a valve construction for internal combustion engines, a hollow rotating valve having a pair of ports at one end and having 15 a conduit formed inside of the same, said conduit opening through the valve at one end and having its other end located adjacent one of the first-named ports, and a second port at the opposite end of the valve 20 in alinement with the other of said first-named ports.

5. In a valve construction for internal combustion engines, the combination of a cylinder having an exhaust conduit and an 25 intake conduit, each of said conduits terminating in branch passages at its inner end leading to the firing chamber of the engine, a hollow rotating valve having ports to communicate with said branch 30 passages and an additional port to communicate with the power chamber of the engine.

6. In a valve construction for internal combustion engines, the combination of a cylinder having an exhaust conduit and an 35 intake conduit, each of said conduits terminating in branch passages at its inner end leading to the firing chamber of the engine, a hollow rotating valve having ports to communicate with said branch 40 passages, an additional port to communicate with the power chamber of the engine, and a conduit communicating with said additional port, said conduit being located inside the valve.

45 7. A valve shaped to inclose a space therein and having ports through which said space communicates with the power chamber of an internal combustion engine and with the exhaust outlet of the same, said valve 50 having a passage opening through the outer surface of the valve and having its inner end in communication with the space inside the valve, said inner end being located adjacent the port through which the said space communicates with the exhaust passage of the engine.

8. A rotary valve shaped to inclose a space therein and having ports through which said space communicates with the power chamber 60 of an internal combustion engine and with the exhaust outlet of the same, said valve having a passage opening through the outer surface of the valve and having its inner end in communication with the space inside the 65 valve, said inner end being located adjacent

the port through which the said space communicates with the exhaust passage of the engine.

9. A valve comprising a body shaped to inclose a space and having ports through which 70 said space communicates with the firing chamber of an internal combustion engine and the exhaust outlet of the same, said valve also having a passage opening at one end through the outer surface thereof and having its inner end in communication with said space, said valve having another port located adjacent the port through which the space communicates with the exhaust conduit, the inner end of said passage being located adjacent said second port. 75

10. A rotary valve comprising a body shaped to inclose a space and having ports through which said space communicates with the firing chamber of an internal combustion engine and the exhaust outlet of the 80 same, said valve also having a passage opening at one end through the outer surface thereof and having its inner end in communication with said space, said valve having another port located adjacent the port through which the space communicates with the exhaust conduit, the inner end of said passage being located adjacent said second port. 85

11. In a valve construction for internal combustion engines, the combination of a cylinder having an exhaust conduit and an intake conduit, branch passages leading from the inner ends of said conduits to the firing 90 chamber of the engine, and a hollow valve having ports, said ports and said passages being so located that the valve ports establish communication simultaneously with the exhaust ports while one of the valve ports 95 opens communication with one of the intake passages in advance of the other port. 100

12. In a valve construction for internal combustion engines, the combination of a cylinder having an exhaust conduit and an 110 intake conduit, branch passages leading from the inner ends of said conduits to the firing chamber of the engine, said branch passages for each conduit being located in the same plane, and a hollow valve having oppositely-located ports, said ports and said passages being so located that the valve ports establish communication simultaneously with the inner ends of the exhaust 115 passages while one of the ports opens communication with the inner end of one of the intake passages in advance of the other port. 120

13. In a valve construction for internal combustion engines, the combination of a cylinder having an exhaust conduit and an intake conduit, each of said conduits terminating in branch passages at its inner end leading to the firing chamber of the engine, a hollow valve having ports therethrough, 125 said ports and said passages being so located 130

that the valve ports register simultaneously with the exhaust passages while one of the ports opens communication with one of the intake passages in advance of the other port, said valve also having a port located beside one of the first-named ports and following the same, and having a passage opening at one end through the outer surface of the valve and having its other end in communication with the inside of the valve and located adjacent the last-named port.

14. In a valve construction for internal combustion engines, the combination of a cylinder having an exhaust conduit and an intake conduit, each of said conduits terminating in branch passages at its inner end leading to the firing chamber of the engine, the branch passages for each of said conduits being located in the same plane, and a hollow valve having oppositely-located ports, said ports and said passages being so located that the valve ports establish communication simultaneously with the exhaust passages while one of the ports opens communication with one of the intake passages in ad-

vance of the other port, said valve also having another port following one of the first-named ports and having a passage opening through the outer surface of the valve, said passage having its inner end communicating with the inside of the valve and being located adjacent said last-named port.

15. In a valve construction for internal combustion engines, the combination of a movable valve for controlling the exhaust from the cylinder of the engine, a conduit within the valve and adapted to deliver into the exhaust passage from the cylinder, and means for actuating the valve to put one end of said conduit into communication with the cylinder when the piston is near one end of its stroke, to have an ejector action and complete the exhaust.

In testimony whereof I have signed my name to this specification in the presence of two subscribing witnesses.

ALPHONSE LAFON.
